MECHANICAL GAS GENERATOR

Laszlo de Csaby, Tulsequah, British Columbia,
Canada

Application September 16, 1938, Serial No. 230,344

1 Claim. (Cl. 261—12)

This invention relates to a mechanical gas generator or gasifier particularly adapted for use with internal combustion engines.

An object of the present invention is the provision of a device for generating a dry gas from liquids capable of being vaporized.

Another object is the provision of a dry explosive gas from liquids, such as crude oil or other liquids of an explosive nature.

Another object is the provision of a gas generator in which the liquid supplied thereto is broken up into its finest molecular state.

Another object is the provision of a device for generating gas from liquid fuels which will result in a saving of the liquid fuels along with a decrease in heat loss and carbonization.

A further object is the provision of a device for generating gas from liquids of an explosive nature, in which the gas is completely generated before it is mixed with the proper quantity of air to make it a violent explosive mixture, thereby reducing the possibility of an explosion in the device.

The main purpose of this invention is to obtain the maximum efficiency from the liquid fuel used in connection with internal combustion engines, together with a high margin of safety by reducing the possibility of premature firing or exploding in the gas generator. The fuel is vaporized and broken up into its very finest state by means of air, centrifugal force, friction, and heat, all in a very limited space, and then it is mixed with the proper quantity of air to make it a highly explosive mixture, this last step, however, being done only immediately before the gas enters the engine.

The present invention consists essentially of a gas generator for internal combustion engines comprising a vaporizing chamber communicating with the intake manifold of the engine, a drum rotatably mounted in the chamber, corrugations formed on the outer surface of the drum and the inner surface of the chamber, means for rotating the drum, means for supplying liquid fuel to the chamber, means for supplying air under pressure to the fuel before it enters the chamber at least to partially vaporize said fuel, and means for heating the fuel as it passes through the chamber, said fuel being further vaporized and broken up in the vaporizing chamber, as more clearly described in the following specification and illustrated in the accompanying drawings, in which

Figure 1 is a front elevation of the generator with the vaporizing drum and cover removed,

part of the front wall and heating plate being broken away,

Figure 2 is a vertical section through the generator taken on the line 2—2 of Figure 1, with the vaporizing drum and cover in place,

Figure 3 is a front elevation of the generator with the cover of the vaporizing drum removed, and

Figure 4 is an elevation of the vaporizing drum.

Referring more particularly to the drawings, 10 is a circular housing having front and rear walls 11 and 12 with a relatively large opening 13 and a smaller opening 14 formed in said front and rear walls, respectively, centrally thereof.

15 An intake pipe 15 having a control valve 16 therein, communicates with the interior of the housing 10 at the bottom thereof while diametrically opposite said pipe, a discharge pipe 17 communicates at one end with the interior of the housing, the opposite end of the discharge pipe being provided with a flange 18 for connection with the intake manifold of an internal combustion engine (not shown). The discharge pipe 17 is formed with a restriction or Venturi passage 20 adjacent its lower end and with a throttle valve 21 above said restriction or passage.

25 A ring or circular partition 22 mounted in the housing 10, is spaced from and concentric with the peripheral wall 23 thereof, to form passages 24 and 25 extending from the intake pipe 15 to the discharge pipe 17. A hollow jet or nozzle 26 formed on the ring 22 and communicating with the space bounded thereby, projects into the discharge pipe 17 and is adapted to discharge into said pipe at the Venturi passage 20. A plurality of spirally disposed partitions 27 are mounted in the housing 10 and form a plurality of spiral passages 28, said passages extending from their entrances 30 outwardly in a spiral and terminating at their outlets 31 adjacent to but within the ring 22.

30 A sleeve 32 is formed on the wall 12 of the housing and extends inwardly from the opening 14. A hollow drive shaft 33 is journalled in the sleeve 32 and extends beyond each end thereof, said sleeve being provided with suitable bearings 34. A pulley 35 is mounted on one end of the shaft 33 and a conical vaporizing drum 36 is mounted on the other end of the shaft, the 35 base of said drum projecting into the opening 13 of the front wall 11 of the housing.

The drum 36 is provided with a hub 37 carried by the shaft 33, forming a chamber 38 within the drum, in which an electrical heating coil 40 is mounted. Leads 41 extend outwardly from the

coil 40 through the shaft 33 to a suitable source of electrical supply, suitable means (not shown) being provided for permitting the coil to rotate without entangling the leads. A plurality of fan blades 42 extend outwardly from the base of the drum 36 approximately to the rear wall 12 of the housing, said blades overlapping the entrances 30 of the spiral passages 28. A spiral band 43 is formed on the outer surface of the drum 36 and extends from the tip rearwardly to the base of said drum. This band forms a spiral groove 44 between its convolutions. The band 43 is relatively narrow at the tip of the drum and gradually widens as it progresses towards the base thereof. Similarly, the various convolutions of the band are closer together at the tip of the drum and gradually get farther apart towards the opposite end thereof so that the groove 44 gradually widens towards the drum base.

A hollow, conical cover 45 fits over but is spaced from the vaporizing drum 36. This cover consists of an inner and outer walls 46 and 47 forming therebetween a chamber 48, in which an electrical heating coil 50 is mounted, said coil being connected to a suitable source of electrical supply in any desired manner. A ring 51 is removably mounted in the concentric opening at the base of the cover 45 between its inner and outer walls. The cover is removably secured to the housing 10 in any suitable manner, such as by bolts 52 threaded into the front wall 12. If desired, flanges 54 may be formed on or secured to the front and rear walls 11 and 12, to which plates 55 and 56 are removably secured, both plates being spaced from the housing.

A spiral band 57, similar to the band 43, is formed on the inner surface of the inner wall 46 of the cover 45, said band forming a groove 58 between its convolutions. The band 57 is arranged so that it overlaps and may even project into the groove 44 of the drum 36 and, consequently, the band 43 of said drum overlaps or may project into the groove 58 of the cover. Actually, these bands and grooves co-operate to form two spiral passages 60 between the vaporizing drum and the cover.

The cover 45 forms a conical vaporizing chamber in which the conical drum 36 rotates. The outer surface of the drum is situated quite close to the inner surface of the vaporizing chamber while both surfaces are corrugated, the corrugations being formed by the bands 43 and 57. This vaporizing chamber communicates with the intake manifold of the engine through the housing 10.

A nozzle 61 is formed adjacent the outer end of the cover 45, said nozzle having a passage 62 communicating with the interior of the cover. A pipe line 63 is connected to the outer end of the nozzle and extends to a fuel tank (not shown). If desired, a suitable pumping device may be employed with the line 63 for supplying fuel to the nozzle under pressure. An air jet 64 formed in the nozzle is adapted to project air under pressure into the passage 62, said air being supplied to the jet through a pipe line 65 which is connected to a suitable source. If desired, suitable means may be employed for varying the pressure and quantity of air supplied to the nozzle, in accordance with the speed of the engine with which this device is used.

A suitable governor 66 is mounted on the drive shaft 33 between the housing 10 and the outer end of said shaft. This governor consists of a collar 67 mounted upon and rigidly secured to

the drive shaft 33 adjacent its outer end; a collar 68 rotatably mounted upon a sleeve 70 projecting outwardly from the rear wall 12 of the housing 10 and surrounding the drive shaft, said sleeve being provided with a flange 71 at its outer end; a plurality of flat springs 72 secured at their opposite ends to the collars 67 and 68, each spring having a weight 73 mounted thereon substantially midway between the ends thereof; and a spiral spring 74 mounted on the shaft 33 and extending from the flanged end of the sleeve 70 to the collar 67. If desired, a cover 75 removably secured to the rear wall 12, may be employed to house the governor 66.

In operation, air under pressure and liquid fuel are supplied to the nozzle 61 through pipes 65 and 63 respectively. The fuel is partially vaporized in the nozzle and then discharged on to the tip of the rotating drum 36. The fuel is either blown or drawn through the chamber formed between the drum and the cover 45, depending upon the speed of the engine on which the device is mounted. The fuel is vaporized in this chamber by heat from the coils 40 and 50 in the drum and cover, respectively. The spiral groove 44 assists the movement of the vaporized fuel towards the opening 13 of the housing 10. At the same time, the vaporized fuel is subjected to centrifugal force and friction as it passes over the surface of the rotating drum as it is thrown outwardly by the drum and strikes the uneven or corrugated surface of the inner wall of the cover. The fan blades 42 direct the vaporized fuel or gas into and through the spiral passages 28. In these passages, the fuel is further broken up by centrifugal force and friction. If desired, additional heat may be applied to the fuel in the spiral passages by any suitable means in the spaces between the covers 55 and 56 and the housing 10, such as, for example, by means of exhaust gases from the engine, which may be directed through said spaces. The gas is then directed by the ring 22 to the nozzle 26, through which it is drawn or blown into the Venturi passage 20 where it is mixed with a suitable quantity of air to make it a violently explosive mixture for firing in the engine. This last-mentioned air enters the housing 10 through the intake pipe 15 and passes along the passages 24 and 25 to the Venturi passage. This air is at least slightly preheated by the gases inside the ring 22 and by the heating means inside the plates 55 and 56, if said heating means is employed.

The partially vaporized fuel expands when it enters the chamber between the vaporizing drum and the cover. This increases the pressure in the chamber but the corrugated drum and inner wall of the cover prevent the gases from passing too rapidly out of the chamber. When the gases enter the housing 10 from the vaporizing chamber, the fan blades 42 direct the gases into the spiral passages 28 and, at the same time, assist in further breaking up the fuel.

From the above it will readily be seen that a device has been provided for generating a dry gas from liquid fuels of an explosive nature, in which the fuel is broken up into its finest molecular state, and which will result in a saving of the fuel.

Various modifications may be made in this invention without departing from the spirit thereof or the scope of the claim, and therefore the exact forms shown are to be taken as illustrative only and not in a limiting sense, and it is desired that only such limitations shall be placed there-

on as are disclosed in the prior art or are set forth in the accompanying claim.

Having now described my invention and the nature of same, what I claim and desire to be protected in, by Letters Patent, is:

A gas generator for internal combustion engines comprising a circular housing having a discharge pipe adapted to communicate with the intake manifold of the engine, an air inlet in the housing spaced from the discharge pipe, an air passage in the housing communicating with the air inlet and the discharge pipe, a conical vaporizing chamber communicating at its base with the interior of the housing centrally thereof, a conical drum rotatably mounted in the chamber, corrugations formed on the outer surface of the drum and in the inner surface of the chamber,

means for rotating the drum, a plurality of spiral storage passages in the housing extending outwardly from the central portion thereof, means for supplying fuel to the chamber at the tip thereof, means for supplying air under pressure to the fuel before it enters the chamber at least partially to vaporize the fuel, said partially vaporized fuel being directed on to the tip of the drum, a heating element in the drum, a heating element in the wall of the vaporizing chamber, means at the rear of the drum for directing fuel from the vaporizing chamber through the spiral passages, and means for mixing the vaporized fuel from the spiral passages with warm air from the air passage before entering the intake manifold of the engine.
